UNITED STATES PATENT OFFICE.

CHARLES W. KECKLER, OF NEWARK, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed December 26, 1919. Serial No. 347,390.

To all whom it may concern:

Be it known that I, CHARLES WILLIAM KECKLER, a citizen of the United States, residing at Newark, in the county of Essex,

5 State of New Jersey, have invented certain new and useful Improvements in Telephone-Exchange Systems, of which the following is a full, clear, concise, and exact description.

10 This invention relates to telephone exchange systems and particularly to circuit arrangements for use at a private branch exchange when such an exchange is employed in connection with an automatic central office.

An object of the invention is to provide means for enabling a subscriber of the private branch exchange system to rapidly establish connections over the trunks extending 20 to the central office without the aid of the operator.

In attaining the object of the invention it is contemplated dividing the subscriber's lines terminating normally in jacks at a 25 manual exchange into groups, each group having access to a group of trunk lines extending from the private branch exchange to the automatic exchange. For example, in a private branch exchange system of 100 30 subscribers' lines and 15 trunk lines, there might be five groups of subscriber's lines of 20 lines each, each group having access to a group of 3 trunks extending to the automatic exchange. Each subscriber's station 35 is provided with switching means whereby his line may be extended at will to the manual switchboard in case a local connection is desired, or over a trunk line to the automatic exchange in case a station at that 40 exchange is desired.

A further feature consists in the use of a novel relay arrangement associated with each trunk, whereby an idle trunk is pre-selected, such trunk being connected to a 45 calling line upon the actuation of switching means at the calling subscriber's station.

A further feature consists in the provision of means for extending a calling line over a trunk of another group in case of an overflow, i. e., when all trunks of the group, with

which said calling line is associated, are busy.

A still further feature rests in the provision of means for indicating to an operator in a system of this nature the trunks 55 and subscriber's lines which are busy.

Referring to the drawing which shows only so much of a telephone exchange system as is necessary for a comprehension of the invention; Fig. 1 shows two subscribers' 60 lines A and B, and three trunk lines D, E, and F with the apparatus therefor. The trunk lines D, E and F extend to an automatic exchange and terminate thereat in line or trunk finders diagrammatically indicated as L. Each line or trunk finder has access to automatic selectors (not shown) and connectors such as C. H represents the station of a subscriber in the automatic exchange; Fig. 2 shows diagrammatically a 70 cord circuit K arranged with a sender S3 and may be of any well known type. For the sake of clearness only two subscribers' stations A and B of the private branch exchange and three trunk lines D, E, and F 75 terminating therein and extending to an automatic exchange are shown, it being obvious that five, ten or twenty stations may be arranged to have access to the three trunks. It will also be obvious that a 80 greater or lesser number of trunks, for example 2 or 5, may be grouped together.

Each subscriber's line is provided with a sender S, which may be of any well known type and a non-locking key. Normally each 85 subscriber's line terminates in a jack in the private branch exchange. By removing the receiver from the switchhook a line is extended to the line jack and a signal individual to the jack is displayed. By removing the receiver and actuating the non-locking key a calling line will be automatically extended over an idle trunk to the automatic exchange. Each trunk is provided with a jack at the private branch exchange switchboard by means of which the operator may connect a subscriber's line 90 thereat with the trunk extending between the private branch exchange and the automatic exchange.

The invention will be more readily understood from a detailed description of the operation of the system. The party at substation A desiring to extend his line over 5 one of a plurality of outgoing trunk circuits to the automatic exchange depresses non-locking key 5 and removes his receiver from the switchhook which causes the operation of marginal relay 6 over the following path: 10 ground, contacts of non-locking key 5, inner armature and back contact of relay 7, ring spring and contact of jack 8, winding of relay 6 and normal contacts of relay 9 to grounded battery. Relay 6 is then held 15 up over a path including ground, normal contacts of relay 10, front contact and outer right-hand armature of relay 6, ring spring and contact of jack 8, winding of relay 6, and normal contacts of relay 9 to grounded 20 battery. Relay 6 upon energization completes a parallel circuit for cut-off relay 7 and line busy signal 18 at its left-hand armature and front contact, and at its inner right-hand armature and front contact completes 25 a circuit for connecting relay 12 of the trunk circuit over the following path: grounded battery, inner right-hand armature and front contact of relay 6, left-hand armature and back contact of transfer relay 30 11 of the trunk circuit D and winding of connecting relay 12 of the trunk circuit D to ground. The lighting of line busy signal 18—associated with the line jack 8 of substation A at the switchboard indicates to the 35 operator that the line is busy and energization of cut-off relay 7 disconnects substation A from the jack 8, thus preventing interference from and the listening in of the operator. Connecting relay 12 upon energization 40 establishes a circuit for transfer relay 51 of trunk D associated with station B, over the following path: ground, front contact and outer right-hand armature of relay 12, outer right-hand armature and 45 back contact of connecting relay 52 and winding of relay 51 to grounded battery. It will be seen that the transfer relays associated with trunk D of all other stations would be energized in parallel with relay 51. 50 The transfer relays in operating prevent this trunk from being seized by other calling lines and render the next idle trunk selectable. Energization of relay 51 completes a 55 circuit for the trunk busy signal 60 over a path including grounded battery, front contact and right-hand armature of relay 51, through signal 60 and the normal contacts of jack 64 to ground. Lamp 60 in lighting indicates to the operator that trunk D is in use. Connecting relay 12 in energizing 60 extends the line of station A over the trunk to a trunk or line finder at the automatic exchange, which is diagrammatically indicated as L. 65 The equipment at the automatic exchange

may be of any well known type in which the switches thereat are operated by interrupting a loop. There may be a number of selectors interposed between the line finder L and the connector C (diagrammatically indicated). 70

When the line of substation A is extended to the automatic exchange by the energization of connecting relay 12, relay 15 in series with the line, will be energized by current from the automatic exchange flowing through the loop of station A to ground at the automatic exchange. Relay 15 in energizing completes, at its armature and front contact, a circuit for slow-to-release relay 9. Cut-off relay 7, line busy signal 18 and connecting relay 12 are held energized through the alternate contacts of slow to release relay 9, the circuit for relay 6 being interrupted at the normal contacts of relay 9, upon the energization of relay 9. Relay 6 is thereupon deenergized. 75 80 85

The subscriber at station A now proceeds to operate the impulse sender S at his station to send out impulses in accordance with the number of the station desired at the automatic exchange. In response to these impulses the switches at the automatic exchange will be set upon the terminals of the desired line and the station such as H will be signalled in the manner well known. With each interruption in the line circuit of station A, the relay 15 thereon will be deenergized thereby opening the circuit of relay 9, but since it is of the slow-to-release type its armature will not release during 90 95 such time. 100

Upon completion of conversation the subscriber at station A restores the receiver to the switchhook, thus opening the loop to the automatic office and causing the switches thereat to return to normal. Relay 15 thereupon deenergizes, thus opening the circuit for relay 9, which in turn deenergizes and opens the circuit for line busy signal 18 and cut-off relay 7 and connecting relay 12. Relay 12 in deenergizing releases all transfer relays in trunk D and extinguishes lamp 60. The line is then ready for another call. 105 110 115

It will now be shown how substation B is automatically connected to the next idle trunk of the group with which it is associated, if the first trunk such as D is being used by one of the stations of the group such as A. If the subscriber at B depresses non-locking key 40 and removes the receiver, marginal relay 46 operates over a path similar to that described for relay 6 of the line for station A. Energization of relay 46 establishes a parallel circuit for cut-off relay 47 and line busy signal 58. It will be remembered that when connecting relay 12 of the first trunk was energized a circuit for transfer relay 51 of trunk D individual to station B was energized and in so doing 120 125 130

prepared a circuit for the connecting relay 62 of the second trunk E of the group. Therefore if trunk D is busy when station B calls, connecting relay 62 of trunk E will be 5 energized over a path extending from grounded battery, inner right-hand armature and front contact of relay 46, left-hand armature and front contact of relay 51, left-hand armature and back contact of transfer 10 relay 61 of trunk E and the winding of relay 62 to ground. Relay 62 will be held up over this path until slow-to-release relay 49 is energized, when it will be held up over a path extending from ground, winding of 15 relay 62, front contact and inner right-hand armature of relay 62 and alternate contacts of relay 49 to grounded battery. Connecting relay 62 in energizing completes a circuit for the transfer relays of all other lines 20 associated with trunk E such as that for station A, over a path extending from ground, front contact and outer right-hand armature of relay 62, outer right-hand armature and back contact of relay 22, and winding of relay 21 to grounded battery. Relay 21 upon 25 energization completes a circuit for the busy signal 70, of trunk E over a path extending from grounded battery, front contact and right-hand armature of relay 21, through 30 trunk busy signal 70 and normal contacts of jack 74 to ground. Signal 70 is thereupon displayed indicating to the operator that trunk E is in use.

Station B is now connected to trunk E 35 and the sender S2 may be operated to set the switches at the automatic exchange and after completion of conversation and restoration of the receiver to the switchhook all relays and signals operated by station B 40 will be restored to normal.

It will now be assumed that all trunks of the group to which stations A and B have access are busy. Since as heretofore explained it is contemplated to have a plurality of groups of trunks with a plurality of subscribers to each group, it is unlikely that all trunks to the automatic exchange will be busy at the same time. The circuits are therefore arranged so that if all the 45 trunks of the group with which the subscriber of a particular group is associated, are busy, the call will be automatically routed to the operator where she may by means of a link circuit K connect the calling subscriber to an idle trunk of another group of trunks. If trunks D, E and F leading to the 50 automatic exchange are busy when the subscriber at station A actuates the non-locking key 5 and removes his receiver, his line will be automatically connected to his line jack 8 and the line signal 14 individual to his line will be displayed. The operator noting the signal, will insert plug 2 of the cord circuit K, (diagrammatically shown) and actuate 55 a listening key (not shown) to inquire his

wants. Upon being informed that a connection with an automatic exchange subscriber is desired, the operator inserts the calling plug 3 of cord circuit K into an idle trunk of another group of trunks leading to the automatic exchange and will either actuate dialing key 4 and her sender S3 to call the desired subscriber or permit subscriber A to call by actuating his sender S depending upon the instructions of the subscriber at station 70 A. Only one group of trunks has been here shown with a plurality of subscribers connected thereto and it will be assumed that there is a second group of trunks at the private branch exchange identical with that 75 shown in Fig. 1 on the drawing.

It has been described how station B was automatically connected to trunk E when trunk D was in use by station A. In a similar manner a third station (not shown) 80 would be automatically connected to trunk F if trunks D and E were in use. Assume that trunk D, E, and F are in use by stations not shown and subscriber A operates non-locking key 5 and removes the receiver from 85 the switchhook. In such case transfer relays 11, 21 and 31 individual to station A and associated with trunks D, E and F respectively would be operated. A path for the energization of relay 6 of station A may 90 be traced as follows: ground, contacts of key 5, inner right-hand armature and back contact of relay 7, ring spring and contact of jack 8, winding of relay 6, normal contacts of relay 9 to grounded battery. 95 Relay 6, thereupon energizes and is held up over a path including grounded battery, normal contacts of relay 9, winding of relay 6, ring spring and contacts of jack 8, inner armature and back contact of relay 7, 100 through the substation loop, outer armature and back contact of relay 7, tip spring and contact of jack 8, right-hand winding of relay 10 to ground. Relay 10 has a high 105 resistance winding and does not energize until the armature of relay 6 completes a circuit for relay 10 over the path extending from grounded battery, inner right-hand armature and front contact of relay 6, left-hand armatures and front contacts of transfer 110 relays 11, 21 and 31 of trunks D, E and F respectively, and left-hand winding of relay 10 to ground. Relay 10 upon energization 115 completes a circuit at its armature and front contact for line signal 14 causing said 120 signal to be displayed until the operator answers. 125

The operator noting line signal 14 inserts answering plug 2 of cord circuit K into jack 8, thus interrupting at the jack contacts, the circuit for line relay 10 which upon deenergizing interrupts the circuit for line signal 14. The operator then actuates a listening key (not shown) and upon being informed by the subscriber that he desires 130

- to call a subscriber at the automatic exchange, the operator inserts plug 3 into a trunk jack of an idle trunk of another group.
- 5 It will be assumed that jack 84 of trunk F belongs to another group. Insertion of plug 3 into jack 84, establishes a parallel circuit for the energization of all transfer relays associated with trunk F over the following path: ground, alternate contacts of jack 84, and thence through the outer right-hand armatures and back contacts of the connecting relays such as 32 and 72 and the windings of the transfer relays such as 31 10 and 71 to grounded battery. Energization of the transfer relays of trunk F opens the circuits of all connecting relays associated with trunk F at the left-hand armatures and back contacts of the transfer relays and prevents this trunk from being selected by a calling subscriber. Insertion of plug 3 in jack 84 establishes a loop for the switches in the automatic exchange causing the line or trunk finder thereat to operate in the 15 manner well known. Subscriber A may now interrupt this loop by means of his sender and set the switches in the automatic exchange after which ringing current will be automatically sent out until the called 20 subscriber responds. Upon completion of conversation and restoration of the receiver to the switchhook by the subscriber at station A the loop will be again interrupted and the switches at the automatic exchange 25 will be restored to normal. By means of a supervisory signal (not shown) in the cord circuit K the operator will be informed that conversation is completed and will remove the plugs of the cord from their associated 30 jacks when all relays will be restored to normal.
- Assume that the subscriber at station A desires the operator, either to complete a connection with another station of the private branch exchange system or over a trunk 35 circuit leading to the distant office.
- Removal of the receiver at station A from the switchhook causes energization of line relay 10 over the following path: ground 40 right-hand winding of relay 10, tip spring and contact of jack 8, back contact and outer right-hand armature of relay 7, through the substation loop, inner armature and back contact of relay 7, ring spring and contact 45 of jack 8, winding of relay 6, and normal contacts of relay 9 to grounded battery. Relay 6 is of the marginal type and will not energize in series with relay 10 due to the high resistance of the winding of relay 10. 50 Relay 10 in energizing completes a circuit through its front contact and armature for line signal 14. The operator observing the signal 14 inserts plug 2 into jack 8 whereupon the circuit for relay 10 is interrupted 55 at the contacts of jack 8, thereby deenergiz-

ing relay 10, which in turn causes line lamp 14 to be extinguished. The operator's listening key (not shown) is then actuated and having ascertained the number desired by the calling subscriber, the operator completes the connection in the usual manner. Upon completion of conversation the usual supervisory signals (not shown) will be actuated whereupon the operator removes the plugs from their associated jacks thus restoring all relays to normal and station A is ready for the next call.

Cord circuit K is provided with a sender S3 so that the operator may call the subscriber at the automatic exchange in case the subscriber at station A so desires.

What is claimed is:

1. In a telephone exchange system, a manual exchange, an automatic exchange, a plurality of groups of trunk circuits extending from said manual to said automatic exchange, a plurality of groups of subscriber's lines terminating in a switchboard at the manual exchange, each of said groups having access to a particular group of trunk circuits, means for enabling a calling subscriber at said manual exchange to extend his line to the automatic exchange over an idle trunk circuit of the group with which his line is associated without the aid of the operator, and means operating automatically to signal the operator to permit the line of a calling subscriber to be extended over an idle trunk circuit of another group of trunks if all the trunks of the group to which the calling subscriber has access are busy.

2. In a telephone exchange system, a manual exchange, an automatic exchange, a plurality of groups of trunk circuits extending from said manual to said automatic exchange, a plurality of groups of subscriber's lines terminating at said manual exchange, each group having access to a group of said trunk circuits, a line signal at said manual exchange for each of said subscriber's lines, switching means for each subscriber's line for actuation by the subscriber, means responsive to the actuation of said switching means for extending said line over said trunk to the automatic exchange, and means responsive to the actuation of said switching means for actuating said line signal if all trunk circuits of the group to which the line has access are busy.

3. In a telephone exchange system, a manual exchange, an automatic exchange, a plurality of trunk lines extending from said manual exchange to said automatic exchange, a plurality of subscriber's lines normally connected to jacks at said manual exchange having access to said trunk lines, a busy signal for each line jack, switching means for each subscriber's line, and relay means responsive to the actuation of said

switching means for seizing an idle trunk line, for disconnecting said line from its associated jack, and for displaying the busy signal of the line.

5 4. In a telephone exchange system, a manual exchange, an automatic exchange, a trunk circuit extending from said manual to said automatic exchange, a plurality of subscriber's lines terminating at said manual exchange, a line relay, a jack and a line signal for each of said subscriber's lines, said subscriber's lines being normally connected to said jacks, a key and a switchhook for each subscriber's line to be actuated by the subscriber, means responsive to the actuation of said key and switchhook, for connecting said line with said trunk circuit and for disconnecting said line from said jack and means responsive to the actuation of 20 said switchhook only for actuating said line signal.

5. In a telephone exchange system, a manual exchange, an automatic exchange, a plurality of groups of trunk circuits extending from said manual to said automatic exchange, a plurality of groups of subscriber's lines terminating at said manual exchange, each group of said lines having access to one of the groups of said trunk circuits, a line relay, a jack and a line signal for each of said subscriber's lines, said subscriber's lines being normally connected to said jacks, switching means actuated by the subscriber for each subscriber's line, and means consisting of relays responsive to the actuation of said switching means for automatically connecting a subscriber's line to an idle trunk of the group with which the line is associated and for disconnecting said line from 40 said jack.

6. In a telephone exchange system, a manual exchange, an automatic exchange, a plurality of trunk circuits extending from said manual to said automatic exchange, a plurality of subscriber's lines normally terminating in jacks at said manual exchange, a line relay and a line signal for each of said subscriber's lines, switching means for each subscriber's line adapted upon actuation to associate said line with an idle trunk circuit, and means for operating said line relay and displaying said line signal if all trunk circuits are busy.

7. In a telephone exchange system, a manual exchange, an automatic exchange, a plurality of subscribers' lines normally terminating in jacks in a switchboard at said manual exchange, a plurality of trunk lines less in number than said subscribers' lines accessible to said subscribers' lines and extending between said exchanges, a non-numerical selecting means associated with each subscriber's line arranged to preselect idle trunks, said means including a connecting relay for each trunk, and means under

the control of a calling one of said subscribers' lines for actuating one of said connecting relays thereby connecting said line to an idle trunk and disconnecting said line from said jack.

70 8. In a telephone exchange system, a plurality of subscribers' lines, a plurality of trunk lines to which said subscribers' lines have access, said trunk lines being less in number than said subscribers' lines, a connecting relay for each subscriber's line associated with each trunk adapted upon energization to connect a calling one of said subscribers' lines with an idle trunk, a barring relay for each subscriber's line associated with each trunk, and means under the control of the calling subscriber for energizing said connecting relay.

75 9. In a telephone exchange system, a manual exchange, an automatic exchange, a trunk circuit extending from said manual to said automatic exchange, a plurality of subscriber's lines terminating at said manual exchange, a jack for each of said lines in which said lines normally terminate, switching means for each line to be actuated by the subscriber, means consisting of relays responsive to the actuation of said switching means for connecting said line with said trunk circuit and for disconnecting said line 80 from said jack and means for each line for controlling switches of said automatic exchange over said trunk circuit.

90 10. In a telephone exchange system, a manual exchange, an automatic exchange, a trunk circuit extending from said manual to said automatic exchange, a plurality of subscriber's lines terminating at said manual exchange, a jack for each of said lines, switching means for each line to be actuated 95 by the subscriber, means consisting of relays responsive to the actuation of said switching means for controlling the connection of said line with said trunk circuit and with said jack and means for each line 100 for controlling switches of said automatic exchange over said trunk circuit.

11. In a telephone exchange system, a manual exchange, an automatic exchange, a trunk circuit extending from said manual to said automatic exchange, a plurality of subscriber's lines terminating at said manual exchange, a jack for each of said lines, switching means for each line to be actuated by the subscriber, a relay responsive to the 110 actuation of said switching means for controlling the connection of said line with said trunk circuit and a second relay responsive to said switching means for controlling the connection of said line with said jack.

12. In a telephone exchange system, a plurality of subscribers' lines, a plurality of trunk lines to which said subscribers' lines have access, said trunk lines being less in number than said subscribers' lines, a 120

connecting relay for each subscriber's line associated with each trunk adapted upon energization to connect a calling one of said subscribers' lines with an idle trunk, a second relay for each trunk for use in pre-selecting idle trunks, and means under the control of the calling subscribers for ener-

gizing the connecting relays and the second relays.

In witness whereof, I hereunto subscribe my name this 19th day of December A. D 1919.

CHARLES W. KECKLER.
